UNITED STATES PATENT OFFICE.

HERMAN BAUER, OF CANNSTATT, GERMANY.

STOP-MOTION FOR BED-FEATHER-TREATING MACHINES.

SPECIFICATION forming part of Letters Patent No. 760,839, dated May 24, 1904.

Application filed March 3, 1904. Serial No. 196,436. (No model.)

To all whom it may concern:

Be it known that I, HERMAN BAUER, a citizen of the Empire of Germany, residing in Cannstatt, in the Kingdom of Würtemberg and Empire of Germany, have invented certain new and useful Improvements in Stop-Motions for Bed-Feather-Treating Machines, of which the following is a specification.

This invention relates to an improved stop-motion for bed-feather-treating machines, and more especially to stop-motion of that class which are periodically started and interrupted so that they can be operated in a more satisfactory and effective manner.

15 The machines heretofore in use for separating, sorting, cleaning and renovating bed-feathers were either continuously-working machines—that is to say, machines having a continuous supply and discharge of feathers to be treated—or machines in which the working is periodically interrupted, so as to permit a new charge of feathers to be supplied to and treated in the same. The former machines were too complicated for practical use, while 20 the latter required careful watching, which increased the expense of running the same. In practice, however, the machines of the second class were more successful, owing to their simpler construction and easier running.

25 The object of this invention is to provide the bed-feather-treating machines referred to with an improved stop-motion by which they are periodically and automatically stopped for receiving the charge of feathers and started automatically, so as to permit the treatment of the feathers and the removal of the impurities separated from the same, the stop-motion controlling also the outlet-valve of the machine, so as to permit the starting of the separating 30 mechanism of the feathers and the opening of the discharge-valve and alternately therewith the removing of the separated impurities and of the cleaned feathers, and, vice versa, the charging of the machine and the closing of the 35 outlets, and for this purpose the invention consists of a stop-motion for bed-feather machines, which periodically starts and stops an agitating mechanism arranged in the feather-

supply hopper and opens the outlet-valve of the machine alternately with the stopping of the agitating mechanism and the closing of the discharge-valve and the connection of suction-fans with the ingoing and outgoing ends for agitating and feeding the feathers and discharging the separated or cleansed feathers. 50 The invention consists, further, in the special construction of the agitating mechanism in the supply-hopper by which the feathers are separated and supplied to the machine; and the invention consists, lastly, in the details of 55 construction of the stop-motion mechanism, as will be fully described hereinafter and finally pointed out in the claims.

In the accompanying drawings, Figure 1 represents a side elevation of a machine for assorting bed-feathers, showing the supply-hopper at the left-hand or ingoing end of the machine removed for the sake of greater clearness. Fig. 2 is an end elevation of the left-hand or ingoing end of the machine, showing 60 the feather-supply hopper and feather-separating mechanism in vertical section. Fig. 3 is a plan view of the machine shown in Fig. 1. Figs. 4 and 5 are respectively a sectional 65 side elevation and a plan view of the stop-motion mechanism by which the feathers are alternately supplied from the supply-hopper to the assorting-machine while the outlet-valve of the machine is open or the supply of feathers interrupted and the outlet-valve closed 70 while the impurities separated from the feathers are removed, and Figs. 6 and 7 are diagrams showing the application of the stop-motion mechanism to a feather cleaning and 75 renovating machine. 80

Similar characters of reference indicate corresponding parts.

In Figs. 1 to 3 of the drawings is shown a machine for assorting bed-feathers, of the well-known construction, to which my improved 90 stop-motion is applied. The machine consists of a casing C, provided with glass panels at its sides and ends. A certain quantity or charge of feathers is supplied intermittently to a supply-hopper H, located alongside of 95 the ingoing end of the casing, the feathers be-

ing separated from each other by means of rotary stirrers in the hopper and drawn into the casing C of the assorting-machine by the current of a suction-fan F, located at the outgoing end of the casing midway of its height. The lighter feathers are separated from the heavier feathers and carried by the current in a diagonal direction through the casing and through an inclined perforated screen C', a 10 valved air-trunk C², and the fan-casing f to the outside, as indicated by the arrows in Fig. 1. The heavier feathers are separated by gravity from the lighter feathers and collected at the lower part of the casing C, from which 15 they are drawn off intermittently by a bottom pipe G, suction-fans F', and discharge-pipe G'. Below the supply-hopper H is arranged a cylindrical trunk H', which is connected by an inclined chute H² with a transverse box H³ at 20 the ingoing end of the casing, said box being provided with a circular opening o and a slide o' between the box H³ and casing of a suction-fan F², so that the connection between the box H³ and fan-casing can be established or interrupted. The slide o' has an opening o², which when placed in register with the opening of the box H³ permits thereby the impurities collected in the box H³ to be drawn out and removed through a gooseneck pipe G', as shown 25 by the arrows at the left-hand side of Fig. 1. In the supply-hopper is arranged a rotary agitator, the vertical shaft a of which has a number of horizontal stirrer-arms a', which beat up the charge of feathers placed in the hopper and 30 deliver it to the cylindrical trunk H' below the same. The vertical stirrer-shaft a is supported in step-and-neck bearings of the hopper, as shown in Fig. 2, and rotated by bevel-gear transmission a² a³ from a horizontal shaft a¹, to 35 which intermittent rotary motion is imparted by a belt-shifting device which is automatically controlled by a stop-motion mechanism that is shown in detail in Figs. 4 and 5 and which also controls the outgoing-valve mechanism 40 and suction-fan and the slide o', so as to place its opening o² in register with the opening o of the transverse box H³ and the casing of the suction-fan F². In the cylindrical trunk H' is arranged a horizontal and transversely-50 slotted partition a⁵, on which the feathers separated by the stirrer-arms a' are dropped. In the slots of the partition a⁵ extend the arms b' of a second agitating device, the horizontal shaft b of which receives rotary motion by a 55 belt-and-pulley transmission b² b³ b⁴ from the shaft a⁴ of the agitating-arms a' in the supply-hopper the arms of the second agitating device being of different length and serving to draw the feathers deposited on the partition a⁵ through the slots of the same, so as to 60 deliver them into the inclined chute H² below the cylindrical trunk H' and through the same into the transverse box H³.

Rotary motion is transmitted to the differ-

ent parts of the feather-assorting machine 65 from a driving-shaft S, which is provided with a fast and loose pulley, as shown at the left-hand side of Figs. 2 and 3. From the driving-shaft motion is transmitted by belt-and-pulley transmissions to the agitating-shafts a 70 and b of the hopper and to the stop-motion mechanism by which the automatic actuation of the agitating devices on the one hand, the outlet-valve C³ of the air-trunk C², the slide o', and the motion of the suction-fans F, F', 75 and F² is controlled.

Repeated tests with feather assorting and cleaning machines have shown that a certain quantity of feathers can be assorted and cleaned in a certain predetermined time. For 80 assorting or cleaning the quantity supplied periodically to the supply-hopper of the assorting or cleaning machine it is necessary to run the machine for a certain period of time and to arrange the stop-motion mechanism in 85 such a manner that the supply of feathers is automatically stopped, so as to permit the removal of the assorted or cleaned feathers, after which the same operation is repeated, and so on. The stop-motion mechanism by 90 which the agitating devices, the outlet-valves, fans, &c., are set in motion, is shown in detail in Figs. 4 and 5. The parts of the stop-motion are also shown in their relative positions in the different figures of the drawings. The 95 stop-motion consists of a cone-pulley d, to which motion is transmitted in any suitable manner from the driving-shaft S. The cone-pulley d is placed on a shaft d', on which is mounted a worm d². The worm d² meshes 100 with a worm-gear d³ on a second upright shaft d⁴, that is supported in neck-and-step bearings of a casing D. (Shown in the upper left-hand corner of Fig. 2 and in detail in 105 Figs. 4 and 5.) The upright shaft d⁴ carries a second worm-gear d⁵, which is located above the worm-gear d³ and which meshes with a worm-gear d⁶ on a third horizontal shaft d⁷, also supported in the casing D, said shaft carrying two cams e and e', which are so arranged 110 that the largest eccentricity of the cam e is diametrically opposite to the largest eccentricity of the cam e'. On the cams e e' rest two levers e² e³, which are extended in opposite direction to each other, one lever being pivoted to one end of the casing and the other lever to the opposite end of the same. The levers e² e³ are provided with suitable weights w w', so as to form frictional contact with the cams e e'. The weighted lever e² is connected by intermediate lever connections with the belt-shifting mechanism of the agitating devices a b in the hopper H in such a manner that by the lowering of the weighted lever e² the belt is shifted from the fast to the loose pulley, and thereby the motion of the agitating devices interrupted. Simultaneously therewith the slide o', which is connected by inter-

mediate lever mechanism with the lever e^3 , is shifted and its opening o^2 placed in register with the opening in the casing of the suction-fan, so that the current will suck the impurities separated from the feathers and collected in the transverse box H^3 from the box and discharge them through the pipe H^4 . As the motion of the cone-pulley and the intermediate worm-gears continues the cam e continues to turn on its axis, so that the lever e^2 is gradually raised to its highest position again, so as to produce the shifting of the belt, by which motion is imparted to the agitating devices of the supply-hopper from the loose to the fast pulley, whereby the agitating devices are again set in motion. Simultaneously therewith the opening in the slide o' is placed out of register with the opening of the casing of the fan F^2 , and thereby the action of the same is interrupted, while the feathers which are supplied by the chute from the supply-hopper H are drawn through the casing of the assorting-machine by the simultaneous opening of the outlet-valve C^3 , that is controlled by a third cam e^5 on the shaft d^7 and intermediate lever connections e^6 , 4^7 , 4^8 , and e^9 . The suction-fan F is simultaneously set in motion and draws the feathers fed through the chute H^2 and separating-box H^3 through the casing, the lighter feathers being separated from the heavier ones and carried by the suction-current through the air-trunk C^2 and casing of the fan F to the outside. The heavier feathers are collected in the lower part of the casing and drawn off at the lower part of the same by the fan F' and pipe G into a suitable receptacle. When the agitating devices in the supply-hopper are stopped, the slide is moved into register with the opening of the suction-fan F^2 and the impurities in the box drawn by suction through the discharge-pipe G' of the suction-fan F^2 . Simultaneously therewith the discharge of the heavier feathers at the lower part of the casing is accomplished by the suction action of the fan F' .

The agitating devices in the hopper H , operated by the cam e and the intermediate belt-shifting devices, and the outlet-valve C^3 are operated alternately with the slide o' and the suction-fan F' , so that the feeding of the feathers and separating of the same and the drawing off of the separated impurities and heavy feathers are alternately performed. As before stated, the automatic action of the stop-motion can only then successfully be employed when the quantity of feathers which are supplied for each periodical treatment is about the same. This requires that the agitating mechanism in the supply-hopper are arranged so as to feed the feathers in a reliable manner. This is accomplished by the two agitating devices, the upper one which serves to beat the feathers and separate them from each other, while the lower one takes them through the

slotted partition and feeds them in downward direction into the supply-chute. This is an essential condition for the successful working of the machine.

The automatic stop-motion described can also be applied to any one of the well-known feather cleaning and renovating machines in which the supply-hopper is connected with a cylinder I , in which the feathers are subjected to the action of steam and then agitated for drying, as shown in Figs. 6 and 7. The speed of the stop-motion mechanism can be adapted to the various speeds required for treating different charges by means of cone-pulleys d , which are shown in the upper left-hand side of Fig. 2 and in Fig. 5, said cone-pulleys permitting the shifting from one set of pulleys to the other, according to the speed required. By setting the stop-motion for the different speeds the period during which each quantity is subjected to the agitating, separating, or cleaning action is periodically regulated, while the feed of the feathers to the machine is regulated by the agitating mechanism in connection with the slotted partition below the supply-hopper. When the agitating devices are not in motion, no feathers are supplied to the separating or cleaning chamber, the gate i of the cylinder I being then in open position for removing the cleansed feathers, as shown in Fig. 6, the operation of the agitating and feeding devices in the hopper being performed alternately with the opening of the discharging-gate of the cylinder.

Having thus described my invention, I claim as new and desire to secure by Letters Patent— 100

1. An automatic stop-motion for the supply and discharge of feathers in assorting, renovating and cleaning machines with periodically-interrupted motion, consisting of feather feeding and discharging devices, continuously-rotating cams arranged in diametrically opposite direction, and intermediate lever connections between said cams and the feeding and discharging devices, so that the feeding devices are operated alternately with the discharging devices, substantially as set forth. 110

2. An automatic stop-motion for feather assorting, cleaning and renovating machines, consisting of feather agitating and feeding devices, suction devices at the ingoing end, and discharging devices at the outgoing end of the machine, continuously-rotating cams arranged in diametrically opposite direction with each other, and intermediate lever connections between said cams and the feeding and discharging devices for alternately operating said feeding and discharging devices, substantially as set forth. 120

3. In a machine for assorting, cleaning and renovating bed-feathers, the combination, 125 with a supply-hopper and a trunk below the same, of a primary agitating mechanism, a secondary agitating mechanism located below

the primary agitating mechanism in said trunk, a partition-plate having slots into which the stirrers of the secondary agitating devices extend so as to draw down the feathers separated by the first agitating device, and a chute connecting said trunk with the casing of the machine, substantially as set forth.

In testimony that I claim the foregoing as my invention I have signed my name in presence of two subscribing witnesses.

HERMAN BAUER.
